United States Patent Office

Des. 194,999
Patented Apr. 9, 1963

194,999

CRATE FOR BOTTLES

James P. Fogerty, Verona, Albert Spaak, Little Falls, and Frank W. Stevens, Rutherford, N.J., and Ira H. Miller, Lambertville, Mich.; said Fogerty, Spaak, and Stevens assignors to W. R. Grace & Co., New York, N.Y., a corporation of Connecticut, and said Miller assignor to Owens-Illinois Glass Company, Toledo, Ohio, a corporation of Ohio

Filed July 20, 1962, Ser. No. 70,995

Term of patent 14 years

(Cl. D58—5)

FIG. 2.

FIG. 3.

FIG. 4.

We claim:

The ornamental design for a crate for bottles, as shown.
